UNITED STATES PATENT OFFICE

JOHN F. DONAHUE AND JOHN A. McMAHON, OF ST. LOUIS, MISSOURI, ASSIGNEES TO JOHN E. MITCHELL COMPANY, OF ST. LOUIS, MISSOURI, A CORPORATION

HEEL-BUILDING PLATE

Application filed March 5, 1930. Serial No. 433,236.

The general object of this invention is to provide a novel plate for use, in conjunction with a suitable machine in building composite heels consisting of a leather base and a rubber tread, to enable the heel parts to be assembled, trued and put under pressure while being maintained in column formation in a chute or log-holder.

In the art of building composite heels of the character referred to, it is the common practice to place in juxtaposition to each other and in parallel rows of considerable length the heel bases and rubber treads, or heels, then to apply cement to the exposed faces of the bases and rubber heels, and after waiting a sufficient time to permit the cement to become "tacky", to assemble and true by hand the respective bases and rubber heels. As each heel is thus assembled it is placed under pressure, either that of the hands or of a press, to cause a thorough union between the leather base and rubber heel.

This method is time consuming, laborious, and frequently results in the leather base and rubber heel being inaccurately assembled.

According to our invention, the composite heel may be assembled trued and subjected to and maintained under the necessary pressure for the requisite length of time in a continuous operation, and with great economy of time and labor.

While the heel-building plate herein described is a distinct subject matter of invention, the invention herein disclosed includes as part of its subject-matter the means by which we are enabled to utilize our improved plate in building composite heels.

Such a machine is of the general nature of the well-known Parks randing machine, but for the purpose of the present invention we have illustrated merely the log-container, and the shaping or truing member, corresponding to the rand applying member of such machine, and a conventional means for applying pressure to the assembled heel to cause its parts to firmly unite and to force it downward in the log-holder or container.

In the accompanying drawing—

Fig. 1 is a top plan view of the upper part 50 of a machine used in assembling the parts

of a composite heel according to our invention;

Fig. 2 is a view in side elevation of our improved heel-building plate;

Fig. 3 is a bottom plan view of the same; 55

Fig. 4 is a longitudinal sectional view of a modified construction of plate, showing a heel comprising a leather base, and rubber tread mounted in position thereon;

Fig. 5 is a bottom plan view of the plate 60 shown in Fig. 4; and

Fig. 6 is a vertical sectional view on a reduced scale showing the manner of assembling the heels in a mould and forcing them downward into a chute or container. 65

The preferred construction of plate is illustrated in Figs. 2 and 3 and comprises a body portion 1 of the size and shape of the heel to be built and having a flat bottom 2 and a convex upper side 3. The breast end 70 4 of the plate is straight or flat and the plate is provided at this end with a projection 5 extending at right-angles to the end 4, said projection being curved or convexed on its inner side as indicated at 6 in Fig. 1, and 75 being upwardly and outwardly inclined, as indicated at 7 in Figs. 2 and 4. The projection 5 constitutes what we term a "heel-gage", inasmuch as, in use, the breasts of the leather base and rubber heel are trued, or brought 80 into alignment, by being forced against the inner side of the said projection. As is well known, the breast of a heel is usually concaved and has a slight pitch or incline in an upward and rearward direction. The inner 85 side of the heel-gage 5 is, as described, correspondingly curved and inclined, so that the breast of the base and rubber heel may abut snugly against the same and be properly trued and aligned. As shown by Figures 4 90 and 6, the heel gage 5 is in all cases of less height than the height of the composite heel assembled thereon, so that as each heel plate with a composite heel thereon is subjected to pressure, as hereinafter described, the bottom of the plate may bear with pressure on the rubber heel beneath it without coming in contact with the heel gage of the plate beneath it.

On the under side of plate 1 we provide 100

a pressure ridge 8, which is preferably located at the breast end of plate and projects usually a distance of one-sixteenth to one-eighth of an inch beyond the bottom surface 5 of the plate. The purpose of this pressure ridge will be presently described.

Referring to Figs. 1 and 6, the numeral 9 indicates the top of a frame or table in which is supported a mold 10 which to all intents 10 and purposes may be considered as the upper end of a container or log-holder 11.

Supported on table 9 is a guide-plate 12 in which is slidably mounted a centering plate 13 having at its forward end, on either 15 side, handles 14 by means of which it may be moved in positions over or to the rear of mold 10, respectively. The conventional pressure means consists of a standard 15 on the upper end of which is pivotally mounted 20 the outer end of lever-arm 16, on which is pivotally mounted at 17 a plunger head 18.

In proceeding according to our invention, we first insert in mold 10 our novel heel-building plate 1. A leather base 19 Figs. 25 4 and 6 is next placed on the plate with its breast 20 against the heel-gage 5 and with its concave or randed side fitting on the convex surface 3 of the plate. The mold 10 is of a size to snugly receive the leather base, 30 as clearly shown in Fig. 1. A rubber heel 21 having rubber cement applied to its inner surface is next placed on the leather base 19 with its tread surface upward as shown in Fig. 4. The rubber heel is always slightly 35 shorter and narrower than the leather base, as the sides and back of the latter must be subsequently ground or smoothed off. It is necessary therefore to center the rubber heel on the leather base. This is effected by the 40 operator grasping the handles 14 and pulling centering plate 13 forwardly, whereby the centering recess 22 thereof will snugly engage the rubber heel and cause it to be properly positioned on the leather base 19 and also to 45 have its breast forced into engagement with the inner surface of the heel-gage 5. The operator next grasps lever arm 16 and forces plunger-head 18 downward into engagement with rubber heel 21, thereby forcing it into 50 firm engagement with the flat side of leather base 19, and at the same time forcing the composite heel and the plate 1 supporting it downward through mold 10 into container 11, as clearly shown in Fig. 6.

55 It will be understood, of course, that in practice the application of pressure is effected automatically, as in the type of randing machine referred to, but as this machine, as such, forms no part of the present invention, 60 we have for the sake of simplicity of illustration, merely illustrated a conventional means of applying pressure to the heels.

Practically all rubber heels have circular projections or cushions 23, Fig. 4, surrounding the nail holes, and at the breast of the

heels these projections are usually three in number, one at each corner of the heel and one in the center. A space, indicated at 24 in Fig. 4, of approximately an eighth of an inch is left between the front edge of the 70 breast and the front sides of these projections or cushions. At first constructed, our improved plates were without the ridge 8 on the bottom, and it was found that in a number 75 of cases the rubber heel and base would separate under pressure along the line of the breast. To overcome this objection the ridge 8 was therefore provided which ridge, in use, will engage the heel in the space provided at 24, adjacent the breast thereof, and operate 80 to cause the rubber heel and base to be thoroughly united along the breast edge.

Some forms of rubber heels are provided with a central recess on their inner side and have a central portion projecting upward 85 from this recess. In such, and similar forms of rubber heels, it may be found desirable to provide a pressure ridge in the center of the bottom of the heel-building plate. We have shown such a ridge in Figs. 4 and 5, the same 90 being of circular formation and indicated by the numeral 25.

We claim:

1. A portable, unitary heel-building plate comprising a body portion of the shape of a 95 heel and having a smooth unobstructed upper surface, and a heel gage projecting upwardly from the breast end of the plate and of less height than the height of the heel to be assembled on the plate.

2. A portable, unitary heel-building plate comprising a body portion of the shape of a heel and having a smooth unobstructed upper surface, and a heel gage projecting upwardly 105 from the breast end of the plate of less height than the heel to be assembled on the plate and shaped to conform to the breast of the heel.

3. A portable, unitary heel-building plate comprising a body portion of the shape of a heel having an unobstructed convex upper side and a heel gage projecting upwardly from the breast end of the plate of less height than the height of the heel to be assembled thereon and shaped on its inner side to conform to the breast of the heel.

4. A portable, unitary heel-building plate comprising a body portion of the shape of a heel and having a smooth unobstructed upper surface and a heel gage projecting upwardly from the breast end of the plate of less height than the height of the heel to be assembled thereon and having a curved outwardly inclined innerside.

5. A portable, unitary heel-building plate comprising a body portion of the shape of a heel and provided with an unobstructed convex upper side and a heel gage projecting upwardly from the breast end of the plate of less height than the height of the heel to be 130

assembled thereon and having a flat outer side and an inner side shaped to conform to the curvature and incline of the breast of the heel.

5 6. A heel-building plate having a body portion of the shape of a heel, a heel-gage projecting upwardly from the breast end of the plate having an inner side shaped to conform to the breast of the heel, and a pressure ridge projecting downwardly from the under side of the plate.

10 7. A heel-building plate having a body portion of the shape of the heel, a heel-gage projecting upwardly from the breast end of the plate and a pressure ridge provided on the under side of the plate at the breast end thereof.

15 8. A heel-building plate having a body portion of the shape of a heel, a heel-gage projecting upwardly from the breast end of the plate and a curved pressure ridge on the under side of the plate at the breast end thereof and extending from side to side of the plate.

20 25 9. A heel-building plate having a body portion of the shape of a heel and provided with a flat under side, and a convex upper side, a heel-gage projecting upwardly from the breast end of the plate and provided with a flat outer side and a curved and outwardly-inclined inner side, and a pressure ridge on its under side at the breast end thereof.

In testimony whereof, we have hereunto set our hands.
